UNITED STATES PATENT OFFICE.

GEORGE F. GRUBE, OF EVANSTON, ILLINOIS, ASSIGNOR TO THE BELBER TRUNK & BAG COMPANY, OF PHILADELPHIA, PENNSYLVANIA, A CORPORATION OF PENNSYLVANIA.

DRAWER-LOCKING DEVICE.

1,375,249.

Specification of Letters Patent. Patented Apr. 19, 1921.

Application filed October 23, 1920. Serial No. 418,963.

To all whom it may concern:

Be it known that I, GEORGE F. GRUBE, a citizen of the United States, residing at Evanston, county of Cook, and State of Illinois, have invented a new and useful Improvement in Drawer-Locking Devices, of which the following is a full, clear, and exact description, reference being had to the accompanying drawings, which form a part 10 of this specification.

This invention relates to an improvement in drawer locking devices for trunks, and more particularly to drawer locking devices for wardrobe trunks, having two compartments hinged together.

One of the objects of my invention is to provide a cheap and efficient locking device, which can readily be connected thereto, without the provision of hinged bars connected to the frame of the trunk.

Another object of my invention is to provide a device of this kind which is so arranged that when one of the drawers is locked, the remaining drawers can be simultaneously locked, or the one drawer can be locked without locking the remaining drawers.

The precise nature of my invention will be best understood by reference to the accompanying drawings which will now be described, it being premised, however, that various changes may be made in the details of construction and arrangement, without departing from the scope of my invention 35 as defined in the appended claims.

Figure 1 is a perspective view of one form of trunk with one form of my invention applied thereto.

Fig. 2 is a horizontal sectional plan view 40 through the drawer compartment of the trunk shown in Fig. 1.

Figs. 3 and 4 are vertical sections through the drawer compartment, showing the upper drawer partially drawn out in one view, to 45 release the locking bar, and pushed in, in the other view to lock the lower drawers by means of the top drawer.

Fig. 5 is a detail view of the rod.

In these drawings, 10 designates the 50 hanger compartment of the trunk which is hinged to the drawer compartment 12, in the usual manner, and 13 are drawers slidably mounted in the compartment 12.

14 is a downwardly opening socket mem- 55 ber, which in the device illustrated is con-

nected to the upper drawer, and 15 is an upwardly opening socket member, which in this case is connected to the lower drawer.

16 is a plate secured to the upper face of the reinforcing member 17 between the bottom drawer and the drawer above it, and which reinforce is secured to the frame of the compartment in the usual manner.

The plate 16 is provided with an eye 18 for the reception of a drawer locking rod 60 19 having rounded ends, and is of sufficient length to extend into both socket members 14 and 15, when in locking position to prevent removal when the drawers are closed.

In the case shown, the upper drawer is 70 provided with a lock 20 whereby the upper drawer may be locked to the frame of the trunk when in its closed position, and through the medium of the rod 19 and its connections with the socket members 14 and 75 15, and the eye 18, prevent the opening of the remainder of the drawers.

Assuming all of the drawers to be locked as shown in Fig. 4, and it is desired to unlock the drawers, the upper drawer is first 80 unlocked and slightly withdrawn to a position similar to that shown in Fig. 3. The front of the upper drawer is then elevated slightly to free the upper end of the rod 19, from the socket member 14. The rod 19 can 85 then be lifted from the socket member 15, and thereby free all of the drawers.

When it is desired to lock all of the drawers, the rod 19 is first inserted in the socket member 15 through the eye 18, and the upper end of the rod is engaged with the socket member 14 by raising the front of the upper drawer. The upper drawer is then closed and locked to restrain the upper end of the rod against movement, and as the 95 lower end of the rod is restrained against movement by the eye 18, all of the drawers below the top drawer will be locked by the rod 19.

If desired, the upper drawer can be locked 100 without inserting the bar, so that all of the drawers below the top drawer are free to be opened.

In the construction shown I have provided means for locking all of the drawers, but if 105 desired, the socket members can be placed on any two drawers to lock the said drawers, together with the drawers between them.

It will also be understood that if it is desired to lock one of the lower drawers 110

with a key lock and lock all of the drawers above it with the rod, it is only necessary to reverse the parts, and if desired the top and bottom drawers can be locked with a key lock, in which case the eye plate 16 can be dispensed with.

10 The advantages of my invention result from the provision of a drawer lock for trunks comprising a removable rod extending across the drawers to be locked, and which is arranged to be retained in its locking position by means of one of the drawers, which is locked in its closed position by means of a locking device.

15 Having now fully described my invention, what I claim and desire to protect by Letters Patent is:—

20 1. A trunk having a drawer compartment, a plurality of drawers slidably mounted therein, locking means to secure one of the drawers to the trunk body, and a locking fixture adapted to lock other drawers and to be itself held in locking position, independently of said locking means, by the 25 first drawer when such drawer is closed and to be unlocked from locking position when the first drawer is slid out.

2. A trunk having a drawer compartment, a plurality of drawers slidably mounted 30 therein, a locking bar adapted to extend in front of certain of the drawers, means to anchor one end of the locking bars, locking means independent of the locking bar to lock one of said drawers to the trunk body, 35 and means independent of the locking means to maintain the other end of the locking bar anchored to the last named drawer when the latter is closed and locked by its locking means.

40 3. A trunk having a drawer compartment, a series of devices slidably mounted therein, a locking bar extending in front of intermediate drawers of the series, means, independent of the locking bar, to lock one of the 45 end drawers of the series to the trunk body, and means independent of the drawer locking means to maintain the locking bar anchored to both end drawers when said lockable end drawer is closed.

45 4. A trunk having a drawer compartment,

a plurality of drawers slidably mounted therein, means to lock one of the drawers to the trunk body, a locking bar, independent of said locking means, extending in front of other drawers, a seat in which one end of the locking bar is adapted to swing, and a seat carried by the first named drawer in which the other end of the locking bar is adapted to swing, said bar being removable from its seats when the first named 60 drawer is unlocked and pulled outward.

5. A trunk having a drawer compartment, a series of drawers slidably mounted therein, a locking bar extending in front of intermediate drawers of the series, seats on end 65 drawers of the trunk engaging opposite ends of the bar, means to lock one end drawer to the trunk body, said bar being removable from its seats when the last named end drawer is unlocked and pulled outward.

70 6. A trunk having a drawer compartment, a series of drawers slidably mounted therein, a locking bar extending in front of intermediate drawers of the series, means to anchor opposite ends of the bar to end drawers of 75 the series, means independent of the locking bar to lock one end drawer to the trunk body, and a stop secured to a fixed part of the trunk body near the point of anchorage of the other end of the bar to the other end 80 drawers and adapted to prevent the outward movement of that end of the bar and thereby lock the last named end drawer from withdrawal.

75 7. A trunk having a trunk compartment, 85 a series of drawers slideable therein, and a locking bar extending in front of intermediate drawers and removably engaging the end drawers and adapted to be held in locking position when the end drawers are closed, 90 and means preventing the opening of one end drawer when the other end drawer is closed, whereby when the latter drawer is closed and locked all the drawers are automatically held closed.

95 In testimony of which invention, I have hereunto set my hand at Chicago, on this 19th day of October, 1920.

GEORGE F. GRUBE.
